MACHINE AND METHOD FOR BINDING BOOKS

Albert Freundlich, New York, N. Y., assignor, by
mesne assignments, to Spiral Binding Company,
Inc., New York, N. Y., a corporation of
New York

Application June 4, 1941, Serial No. 396,550

31 Claims. (Cl. 11—1)

This invention relates to machine and method for making book constructions, particularly those of the type in which a plurality of sheets are loosely bound together by means of a helical or spirally-shaped binder and an example of which is shown in United States Patent No. 2,279,193 issued to William A. De Hart on April 7, 1942.

The principal object of the invention is to provide an efficient and durable machine capable of rapidly binding a book of the indicated type with a helical wire which is formed, threaded through the perforations provided along the binding edge of the book, cut to proper length and locked in position in the book during one cycle of operations of the machine.

Other objects and advantages of the invention will be in part obvious and in part pointed out in the following detailed description of the invention.

Before taking up the detailed description of the invention, however, it is considered advisable to point out that the invention broadly involves mechanism for shaping each set of successive perforations in the book so that it defines a passageway which conforms in curvature to the curved portion or segment of the helical binder which will extend therethrough, means for securely clamping the book in its shaped condition during the binding operation, means for forming a wire into a helical shape and automatically feeding it into the shaped sets of perforations along the binding edge of the book of sheets, means for controlling the duration of the period during which the formed wire is fed into the book, thereby controlling the length of the helical binder, and means for cutting the ends of the portion of the wire threaded into the book and for turning such ends inwardly so as to lock the binder in position in the book. Incorporated in the machine are also other control means which come into operation under certain conditions to perform their various functions.

The invention consists, accordingly, in the novel features of construction, arrangements and combinations of parts embodied, by way of example, in the machine hereinafter described and illustrated in the accompanying drawings, in which Fig. 1 is an elevational view of the rear of the machine; Fig. 2 is a vertical sectional view taken along a line passing approximately midway through the machine; Fig. 3 is a view substantially similar to Fig. 2 but looking in the opposite direction; Fig. 4 is a rear elevational view of the upper portion of the machine, some of the parts being omitted to show the arrangement of the

cutting and bending units and the associated instrumentalities; Fig. 5 is an enlarged detailed rear view, partly in section and partly broken away, of the forming die and the devices for guiding the wire through the book; Fig. 6 is a vertical cross-sectional view taken along the line 6—6 of Fig. 5; Fig. 7 is a horizontal sectional view of the machine showing in plan view the mechanism for controlling the feeding and forming of the wire; Fig. 8 is a sectional view taken along the line 8—8 of Fig. 7; Fig. 9 is a detailed front elevational view of the metering mechanism illustrated in Fig. 7 for controlling the duration of feed of the wire; Fig. 10 is an enlarged detailed view of a portion of the mechanism shown in Fig. 3 of the drawings but looking from the opposite direction and illustrating the manner in which the members for rearranging the sheets of the book operate during the initial forward throw of the operating handle; Fig. 11 is a view similar to Fig. 10 showing the parts in an advanced position and showing also in dotted outline the position of the sheet arranging mechanism at the end of the forward throw of the operating handle; Fig. 12 is a sectional view of the cutting and bending mechanism taken along the line 12—12 of Fig. 13; Fig. 13 is a front elevational view of a cutting and bending unit; Fig. 14 is a side elevational view of the unit illustrated in Fig. 13; Fig. 15 is a front elevational view of the upper end portion of the other cutting and bending unit; Fig. 16 is a rear elevational view, partly in section, of the pin clutch mechanism for controlling the operation of the main cam shaft; Fig. 17 is a top plan view, partly in section and partly broken away, of the mechanism for controlling the adjustment of the rear portion of the table; Fig. 18 is a side elevational view of the mechanism illustrated in Fig. 17 of the drawings; Fig. 19 is a side elevational view of a portion of the instrumentalities for starting the operation of the machine and for rendering it inoperative; Fig. 20 is a side elevational view of a portion of the mechanism for controlling the operation of the side gauge; Fig. 21 is a cross-section view taken along the line 21—21 of Fig. 22; Fig. 22 is a view similar to Fig. 20 showing the position of a portion of the side guide actuating mechanism after such mechanism has been operated, and Fig. 23 is a top plan view, partly in section, of the forward portion of the operating table of the machine and illustrating the mechanisms for adjusting the lateral or fore and aft position of the table.

In the drawings, and referring more particu-

larly to Fig. 1 thereof, the reference numeral 1 designates the wire from which the binders are made, the wire being drawn from a wire reel 2 which is mounted on the base of the machine and which is adapted to hold a considerable length of the wire so as to provide a supply of wire sufficient for the formation of a considerable number of the spiral binder elements. The wire 1 passes upwardly from the reel 2 into an oil cup 3 which is preferably filled with cotton or other absorbent material saturated with a light lubricant which becomes adhered to the exterior surfaces of the wire in its passage through the oil cup and facilitates the feed of the wire through the machine. The wire then passes through two series of straightening grooved rolls 4 and 5 (see Figs. 1 and 2) which remove any kinks or bends in the wire. After leaving the rolls 4 and 5, the wire passes through a guide tube 6 positioned between a pair of feed rolls 7 and 8, the latter of which draw the wire up from the reel 2 and force it up a guide tube 9 and into a spiral forming die which is indicated generally by the reference character 10 (see Fig. 5) and which is composed of a block having a bore 11 disposed at right angles to the guide tube 9. It will be noted from Fig. 5 of the drawings, that the tube 9 extends into the die 10 and is in communication with the bore 11 of the die. The discharge end of the guide tube 9 communicates also with the beginning of an internal spiral groove 12 formed in the wall of the bore 11 and spiralling to the left, as viewed in Fig. 5, toward the discharge end of the bore 11. Extending through the bore 11 is a mandrel or shaft 13 which is somewhat tapered in form so that its inner end fits snugly in the bore 11 while its other end is spaced from the portion of the wall of the bore 11 provided with the internal groove 12. Thus the mandrel 13 is properly supported in the bore 11 by its inner end and its outer end cooperates with the internal groove 12 to form the wire fed into the die into a spiral shape. The mandrel or shaft 13 is movable longitudinally of the bore 11 for adjustment with respect to the spiral groove 12 through a threaded rod 14 which is connected to the inner end of the shaft and extends beyond the inner end of the die block 10, and a nut 15 adapted to bear against the associated end face of the die 10. The outer end of the mandrel or shaft 13 carries an enlarged plug-like portion or pilot 16 having formed in its exterior surface a spiral groove 17 into which is fed the convolutions of the spiral formed by the groove 12, the groove 17 of the pilot 16 guiding the spirally formed wire forwardly to the place where such wire will be threaded into the apertures of the book. The wire leaving the forward end of the pilot 16 passes around the top end of the book and then downwardly into the first of the series of perforated holes provided along the binding edge of the book. Prior to the entry of such wire into the perforations of the book, such perforations are first aligned in an arcuate manner by mechanism which will be hereinafter more fully explained. When a sufficient length of wire has been fed to provide a complete spiral binder element, cutting and bending mechanism comes into operation to cut the portion of wire threaded in the perforations to its proper length and to bend the ends thereof in a manner which will also hereinafter be more fully explained. In this connection it may at this time be pointed out, that the outer projecting end of the pilot 16 is cut away to provide a space into which the cutting

and bending mechanism at this end of the machine may enter to perform its operations. By varying the pilot 16 with relation to the die 10, through the medium of rod 14 and nut 15, variations in the wire pitch and the diameter formed in the die may be corrected or effected. Thus, by adjusting the nut 15 so that the pilot 16 is moved slightly away from the die 10, the turn or coil of the spiral wire issuing from the latter and in the region of the neck of the mandrel 13 will be stretched, while by adjusting the pilot 16 towards the die 10, such turn or coil will be compressed. This stretching or compressing of the wire will be sufficient to correct small inaccuracies in the spiral wire formed by the die 10 and these corrections are not influenced by the pilot's spiral groove 17 which is wider than the diameter of the wire. Minute adjustments may also be thus made of the exit end of the groove 17 of pilot 16 with respect to the first of the series of perforations in the book. The pilot 16 as well as die 10 can also be adjusted as a unit by varying the position of die 10 in its supporting guide or bracket 18, the die being maintained in its adjusted position by means of the threaded hand bolt 19 which extends through a threaded aperture in the top of the bracket or block 18 and into the guideway in which is positioned the die 10.

30 The mechanism for aligning the perforations of the book to be bound is controlled by a manually operated handle A which, as is shown more clearly in Figs. 1 and 2 of the drawings, is carried on the outer ends of a pair of arms B. The other ends of the arms B are fixedly connected to a rod C extending longitudinally along the rear of the machine and rotatably supported at its ends by two bearing brackets 20, 21 (see Fig. 1). The bearing brackets 20 and 21 are slidably and rotatably mounted on a pair of spaced, longitudinally extending, stub shafts or rods which are fixedly secured to the frame of the machine and only one of which can be seen in the view illustrated in Fig. 1 of the drawings, such rods being indicated by the reference numeral 22. The shaft C and the rod 22, at the left hand side of the machine, as viewed in Fig. 1 of the drawings, are separated and disconnected. The rod 22 at the right hand side of the machine, as viewed in such figure is, however, connected to the shaft C by a bar 24 which is fixedly secured to the shaft or rod 22 but is movable relative to the shaft C which extends therethrough. Intermediate the bar 24 and the adjacent handle arm B of the operating handle and encircling shaft C, is a coiled spring 25 which normally urges the unit or carriage comprising the handle A, arms B, B and shaft C towards the opposite side of the machine. Fixedly secured to the shaft C intermediate the brackets 20 and 21 is an elongated supporting bracket 26 on the upper surface of which is mounted a plate 27, as is shown more clearly in Figs. 2, 10 and 11 of the drawings. The forward edge portion of plate 27 projects forwardly beyond the forward edge of the bracket 26 and has secured thereto a series of hook-like members 28, the shanks of such hook-like members everlying the plate 27 and the hooked ends 29 thereof extending forwardly from the forward edge of the plate 27. Each of the hooked ends 29 is of a radius determined by the diameter of the spiral binder to be inserted in the perforations and is preferably of the same diameter. The hooked ends 29 are also offset to the same degree as the pitch of the coils in the spiral binder to be inserted.

Thus when such ends 29 are inserted into the apertures of the book they will shape each set of successive perforations so that it defines a passageway which conforms in curvature to the curved portion or segment of the helical binder which will extend therethrough. This operation takes place at the beginning of the forward movement of the handle A in the operation of the machine. At the time that the handle A is moved forwardly to cause the hooked ends 29 of the members 28 to come into engagement with the sets of perforations in the book D, the latter is lying in unclamped condition on the working table 23 of the machine with its binding edge against two stop or guide members 38, 38 (see Figs. 4 and 10). As the forward free or hooked ends 29 of the members 28 engage with the series or sets of perforations provided along the binding edge of the book, as is shown in Fig. 11 of the drawings, the free pages of the book are shifted so that the apertures of each set assume an arcuate form conforming to the configuration of the hooked ends 29 and are also offset to the same degree as the pitch of such ends. In their passage through the apertures of the superimposed sheets of the book the hooks thus form the apertures to the shape desired and at the same time free the holes of any material which may have been retained therein as a result of drilling or punching such apertures. Due to the fact that the free ends of the members 28 are pointed, the hooked ends in their passage through the several sets of apertures in the book will first align the apertures into substantially the correct position before forming them into the shape of a segment of a helix.

The shaft C and bracket 26 are enclosed by a cylindrically-shaped housing E which is attached at its ends to the supporting brackets 20 and 21 (see Figs. 1 and 10 and 11). Mounted upon the housing E are a pair of clamp operating means comprising two set screws 31, 31, which are in threaded engagement with and extend through the brackets 32, 32 secured to the exterior surface of the housing E, the set screws 31, 31 being fixed in their adjusted positions with respect to the brackets 32, 32 by the usual lock nuts. The forwardly projecting ends of the set screws 31, 31 are adapted to engage with and depress a pair of spring-pressed plungers 33, 33 provided at each end of a clamp body 34 (see Figs. 1 and 11 and more particularly the latter which shows in dotted outline the manner in which the set screws engage such plungers). The plungers 33, 33 normally rest on the upper ends of two clamp guides 35, 35 to maintain the clamp body 34 in raised position, as is illustrated in Figs. 1 and 10 of the drawings. The clamp body 34 which is slidably engaged at its ends with the opposed grooves in clamp guides 35, 35 is provided intermediate such guides with a clamp member or shoe 36 (see Fig. 10) adapted to come into engagement with the top surface of a book D on table 23 when the plungers 33, 33 are depressed or retracted by the set screws 31, 31, as is shown in dotted outline in Fig. 11 of the drawings. The shoe 36 is connected to the clamp body 34 by a pair of T-shaped guide members 43, 43 (see Figs. 1 and 10) which are slidably mounted in a T-shaped guideway 37 provided along the lower longitudinal edge of the body 34 of the clamp. The shoe 36 is adjustably connected to each of the T-shaped guide members 43, 43 by means of a bolt 44 whose head is positioned in a traverse slot 38' provided in the under surface of the shoe 36.

5 36, as is shown in Fig. 11 of the drawings, and whose shank extends up through the shoe and into the vertical body portion of the T-shaped guide member, whereby the shoe 36 is enabled to be moved forwardly and rearwardly with respect to such members and consequently the clamp body 34. When the shoe 36 is properly adjusted the bolts 44, 44 are tightened to secure the shoe in position. Mounted in the forward 10 arm of the T-shaped guideway 37, intermediate the two T-shaped guide members, is a rack bar 39 whose ends are in engagement with the spaced guide members 43, 43 provided on the shoe 36. The teeth of the rack bar 39 are engaged by a pinion 39' provided on the lower end of a stem 40 which extends up through and is in threaded engagement with a lock nut 41 resting on a horizontal surface of the clamp body 34, the upper end of the stem 40 being provided with a hand-wheel 42 by which the pinion may be rotated. It will thus be seen that the shoe 36 is adjustable both in a longitudinal direction and in both transverse directions to obtain an accurate position of the shoe 36 with respect to the hook-shaped ends or positioning fingers 29. The shoe 36 is provided along its rear edge with a projecting ledge having a series of open slots 45 formed therein in such manner that when the clamp is in position on the book, as is shown in dotted outline in Fig. 11 of the drawings, such slots become aligned with the formed apertures of the book. In this portion of the shoe 36, the projecting portions or teeth formed by the slots 45 will be positioned intermediate the sets of apertures thus affording a firm support or clamping means for the portions of the sheets intermediate the apertures or perforations thereof. The slots 45 are each formed to have an average angle of the helix and are of sufficient width so as not to interfere either with the removal of the positioning fingers 29 or the threading of the binder through the apertures of the book.

45 It will be understood from the foregoing that on the forward throw of the handle A, the positioning fingers 29 first engage the sets of apertures in the book D to arrange them into proper form for the reception of the spiral binder. When the handle A has been moved forwardly so that the set screws 31, 31 come into engagement with the spring-pressed plungers 33, 33, as is shown in dotted outline in Fig. 11 of the drawings, such plungers are depressed thereby causing the clamp body 34 to slide down in the guide 35, 35 and bring the shoe 36 into engagement with the top of the book D. Thus at the completion of the forward movement of the handle A, the sheets of the book have been arranged so that the perforations thereof are in proper shape for the reception of the spiral binder and the sheets of the book, as thus arranged, are clamped in their adjusted positions on the table 23 of the machine by the shoe 36 of the clamp 34. The handle A is then moved rearwardly by the operator to remove the positioning fingers 29 from the apertures of the book and during such rearward movement the fingers 29 pass upwardly through the slots 45 of the shoe 36. By reason of the fact that the book is clamped in position so that the interior surfaces of the apertures in the book are relatively fixed, the fingers 29 during their outward or returning movement are cammed in the direction of the pitch of the hole to shift the carriage of which the handle is a part to one side against the tension of the spring 25, the spring 25 immediately returning the carriage

to its normal position after the hooks have cleared the apertures in the book.

The backward throw of the handle A causes also an operating arm 46 (see Figs. 1 and 19) fixedly secured to the left hand end of shaft C, as viewed in Fig. 1 of the drawings, to come into engagement with the free end of a starting lever 47 pivotally mounted at 47' on a side frame of the machine, to start the feeding and forming of the wire, as has been previously explained. When the starting lever 47 is thrown forwardly by the handle A through arm 46, it displaces a lever 48 which is pivoted intermediate its ends on the brackets 49 and is connected at its outer end to the lever 47 by means of a link 50. The other or inner end of the lever 48 carries a wedge 51 (see Fig. 1) which controls the operation of a pin clutch of conventional construction, such as is shown for example in Fig. 16 of the drawings and designated generally by the numeral 52. The displacement of lever 48 by the forward movement of lever 47, causes the wedge 51, which is similar to the wedge 51' shown in Fig. 16 of the drawings but positioned at a different place with respect to the clutch 52, to be withdrawn from the path of a stop lug 53 mounted on a pin 54 which is provided on the male member 58 of the clutch 52. The pin 54 is normally urged by a spring 55 toward the female clutch plate 56 which is rotatably mounted on a main cam shaft 59 and which is provided with a plurality of recesses 57 adapted to receive the outer end of the pin 54. When the pin 54 is seated in a recess 57, the female member 56 of the clutch 52 is united with the male member 58 of such clutch and with the main cam shaft 59 to which the male clutch member 58 is fixedly attached. Fixedly secured to the female member 56 and rotatably mounted on shaft 59 is a worm wheel 66 which is in engagement with a worm 65 secured to a transverse shaft 63. The shaft 63 is mounted at its ends in bearing members provided on the housing 64 of the reduction gear box and is connected to a motor 60 (see Fig. 1) which is mounted on the frame of the machine through a pulley wheel 62 secured to such shaft and connected by a strap or belt 61 to a pulley wheel provided on the driving shaft of the motor 60. It will thus be seen that when the pin 54 engages a recess 57 in the female clutch member 56, the shaft 59 is connected in driven relation to the motor 60 through worm wheel 66, worm 65, shaft 63, pulley 62 and belt 61, and through such connections is caused to be rotated. The rotating of shaft 59 causes a series of cams secured thereto to be rotated whereupon there is set into operation various mechanisms controlled by such cams.

Returning again to the wedge 51, this wedge is in engagement with the lug 53 at the start of each cycle of operation of the machine and during such engagement the cam surface thereof through lug 53 is holding the spring-pressed pin 54 in retracted position with its outer end out of engagement with the recess 57 in the female clutch member, thereby disconnecting the cam shaft 59 from the motor 60. When lever 47 is actuated on the backward throw of handle A to withdraw wedge 51 from the path of lug 53, the pin 54 is enabled to engage with an associated recess 57 to connect shaft 59 in driven relation with the motor 60 and thereby to cause such shaft to start its rotational movement, the shaft rotating through one complete revolution for each cycle of operations of the machine. As soon as lug 53 moves past the withdrawn wedge 51, the latter returns to its

normal advanced position where it is again in the path of lug 53 due to the fact that the operating handle A after such operation is returned to its starting position, thereby releasing the pressure of operating arm 46 on lever 47. As the shaft 59 rotates, the lug 53 comes into engagement with the second wedge 51' shown in Fig. 16 of the drawings and positioned from the wedge 51 at an angle of approximately 90° or one-quarter turn of the male clutch member 58. If the wedge 51' has not been withdrawn, in a manner which will be hereinafter more fully explained, the lug 53 will through the cam face of wedge 51' be forced outwardly against the tension of its associated spring 55, thereby disconnecting the pin 54 from the engaged slot 57 and breaking the driving connection of the shaft 59 with the motor 60. During this initial 90° rotation of shaft 59, certain of the cams mounted on such shaft cause certain mechanisms to come into operation.

The cams mounted on shaft 59 include a pair of spaced clamp elevating cams 70, 70, a cutter operating cam 71, a cutter elevating cam 72 and a spiral starting or feed roller control cam 73. The first of these cams to come into operation during the rotative movement of shaft 59 is cam 73 which controls the operativeness of the feed rollers 1 and 8 to feed the wire 1 from the reel 2 to the die 10 and to feed the spirally formed portion of such wire into the apertures of the book D which, as has been explained, is properly arranged and clamped in position on the table 23 of the machine by the shoe 36 of the clamp body 34. The feed rollers are driven continuously during the operation of the machine but are normally in separated condition so as to be inoperative to feed the wire to the forming die 10. Rotative movement is imparted to the feed roller 7 from the motor 60 (see Fig. 1) which, as has been explained, is connected to the transverse shaft 63 by the belt 61 and pulley wheel 62. Mounted on and secured to shaft 63 is a gear 74 which meshes with gear 75 rotatably mounted on a stub shaft 76 secured at one end in a boss 77 formed on the gear housing 64, as is shown more clearly in Fig. 3 of the drawings. Integral with the gear 75 is a pulley wheel 78 which carries the upper end of a strap or band 79 (see Figs. 1 and 3), the lower end of such band being carried by a pulley wheel 80 mounted on a transverse shaft 81 rotatably mounted on a bearing hanger 82 (see Fig. 2). The shaft 81 also carries a cone pulley 88 which is connected by means of a band or strap 89 to a cone pulley 90 provided on the shaft 91 to which the feed roller 7 is connected. By this mechanism, feed roller 7 is maintained in constant connection with motor 60 and is thus continuously driven while the latter is operating. Continuous rotative movement is imparted to feed roller 8 from shaft 91 by means of a gear 92 which is mounted on such shaft and which meshes with a gear 93 secured to the shaft 94 to which the feed roller 8 is also secured, as is shown more clearly in Fig. 7 of the drawings. During the rotative movements of feed rollers 7 and 8, a balanced tension on the two belts 79 and 89 is attained by the mounting of the shaft 81 on the hanger support 82 which is in the form of a bell crank lever. As is shown more clearly in Fig. 1 of the drawings, one arm of the support 82 is tensioned by a spring 83 which is connected to an adjustable standard 84 and the other arm of such support is connected at the point 88 to one end of a link 85 which is supported at its other end

by a depending bracket 87 fixed to the frame of the machine. The standard 84 is also adjustably connected by its portion 84' to the link 85 and rigidly supports the free end of link 85 in its adjusted position. Thus the initial tension applied to the belts 79 and 89 is obtained through the medium of the adjustable standard 84 and the link 85, while an equalizing tension is applied through the medium of the spring 83.

The actuation of cam 73 brings into operation mechanism which will render the continuously rotating feed rollers 7 and 8 operative to feed the wire to the forming die 10 for a predetermined period of sufficient duration to provide for the formation and the threading through the book D of a spiral binder of a predetermined length. At the start of the cycle of operations and before the shaft 59 is caused to rotate in the manner previously explained, the cam 73 is in the position shown in Fig. 2 of the drawings with a cam roller 95 resting on a portion of the cam immediately before the lifting surface portion or exterior surface of the tooth-shaped portion 73' of the cam, it being understood that the cam 73 will rotate in the direction of the arrow shown on such cam. When the shaft 59 commences its rotative movement, the lifting surface of the cam portion 73' moves in a counterclockwise direction as viewed in Fig. 2 of the drawings, or in the direction indicated by the arrow and causes the cam roller 95 to roll up on such surface, thereby lifting such cam roller together with the vertically disposed link or arm 96 to which said cam roller is attached. The link 96 is provided at its lower end with a fork-shaped portion which straddles a reduced portion 98 (see Fig. 16) of a collar 99 mounted on the shaft 59 adjacent to the cam 73 so that such forked end 97 of the link 96 is slidably confined between the collar 99 and the cam 73. The upper end of the link 96 is pivotally connected to the outer end of a lever 100 whose other end is rotatably and slidably supported on a shaft 101, which itself is slidably supported in a bearing bracket 102. As is shown more clearly in Fig. 8 of the drawings, the shaft 101, intermediate the lever 100 and a second lever 103 also pivotally mounted on such shaft, is provided with an enlarged, rectangularly-shaped portion 104 adapted to be received in enlarged recesses or slots provided in the opposed faces of the hub portions of the levers 100 and 103 and thereby normally to connect or to lock such levers together so that they function in the nature of a bell crank lever on the shaft 101. The slots provided in the hubs of the levers 100 and 103 each flare outwardly at their outer ends to enable the levers to be shifted relative to the enlarged portion 104. Thus lever 100 is enabled to become disconnected from the portion 104 and to drop downwardly when the cam 73 has rotated past its highest point. The lever 103, however, will remain in its displaced position during the period that the link 96 and lever 100 return to their normal positions and until the lever 103 is further displaced to cause it to return to its normal at rest position, in a manner to be hereinafter more fully described.

The raising of the link 96 causes the levers 100 and 103 which are at this time united by the enlarged key portion 104 of the shaft 101, to rotate in a clockwise manner, as viewed in Fig. 2 of the drawings, and thereby to shift a link 105 connected to the other end of lever 103 (see Figs. 2, 7 and 8) longitudinally in a direction towards the front of the machine. The link 105 is con-

nected at its forward end by a universal joint 106 to a control lever 107 which, as is shown more clearly in Fig. 7 of the drawings, is pivoted intermediate its ends at the point designated 108 and carries at its forward end a cam roller 109. Thus when the link 105 is shifted toward the front of the machine, the lever 107 through the universal joint connection 106 will be caused to pivot about the point 108 to the dotted line position shown in Fig. 7 of the drawings and thereby cause the cam roller 109 carried thereby to come into engagement with and press against a cam member 110 provided on the free end of a lever 111 to cause the latter to move to the dotted line position shown in Fig. 7 of the drawings, about its pivot 112. The lever 111 adjacent its pivoted end carries a cam-shaped projection 113 which is normally in engagement with the adjacent face of a block 114 slidably mounted in a guide 115, the engagement of the block 114 and cam projection 113 being maintained by means of spring 116 (see Fig. 8). The block 114 carries the shaft 91 upon which the feed roller 7 is mounted. It will be evident from the foregoing that the raising of link 96 by cam 73 and the consequent shifting of lever 111 to the dotted line position illustrated in Fig. 7 of the drawings causes the cam projection 113 on such lever to force the block 114 to the left, as viewed in Figs. 7 and 8 of the drawings, against the tension of spring 116, thereby carrying the shaft 91 and the feed roller 7 toward the feed roller 8 mounted on the shaft 94 and bringing such rollers into cooperative relation to feed the wire toward the spiral forming die 10. The pivot 112 of the lever 111 comprises a pin which extends transversely through a block 117 mounted in the guideway of the guide 115. The block 117 is adjustably secured in position in such guide by means of an adjustable screw member 118 which extends through the adjacent end closure of guide 115 and is provided with a lock nut which engages with the outer face of such end closure, the projecting end of the member 118 being provided with a hand-wheel whereby adjustment of such member may be attained. With this construction it is possible, therefore, to make an adjustment in the range of movement of block 114 and consequently the feed roller 7 to provide for varying thicknesses of wire to be fed to the forming die 10.

By the time that the two feed rollers 7 and 8 have been thus brought into cooperative relation to grip and feed the wire, the cam 73 has been rotated by the shaft 59 to its highest point so that immediately thereafter the cam roller 95 and link 96 drop back to their normal positions with the cam roller 95 coming into engagement with the portion of cam 73 in back of the tooth-shaped portion 73' thereof. With the return of link 96, lever 100 likewise returns to its lowermost normal position. As has been previously mentioned, the return movement of lever 100 is made possible because of the form of its connection with the enlarged key portion 104 of the shaft 101, the lever 100 becoming released from such portion 104 and thereby breaking its positive connection with shaft 101 and consequently lever 103.

The lever 103 in addition to bringing the rollers 7 and 8 into cooperative relation in the above described manner, also starts the operation of a metering device for controlling the length of the period that such rollers will remain in cooperative relation at the same time

that the feed rollers 7 and 8 begin their feeding of the wire to the forming die 10. The metering device comprises a standard 133 (see Figs. 7 and 9) mounted on the lever 107 which, as has been explained, is controlled by lever 103 through link 105 and universal joint 106. The standard 133 has rotatably mounted on its upper end a roller 132, which is adapted to come into engagement with the under surface of a shoe 131 provided on the outer end of a lever 130 which is pivotally supported intermediate its ends at 129 upon a pair of upstanding, spaced ears formed on a bracket 126 secured to the frame of the machine. The other end of the lever 130 rests on the upper end of a vertically disposed shaft 128 which is slidably and rotatably mounted in a pair of spaced bearing arms formed on said supporting bracket 126 and is normally urged to its uppermost position by means of a helical spring seated between the lower bearing arm and a spool 127 secured to the shaft 128 intermediate such bearing arms. The lower end of the shaft 128 is provided with a clutch plate 124 adapted to engage a clutch plate 123 mounted on the upper end of a shaft which is rotatably mounted in a closed bearing housing 122 supported by the frame of the machine. Also secured to the shaft bearing the plate 123, is a worm wheel 121 which meshes with a worm 120 provided on the feed roller shaft 94, as is shown more clearly in Fig. 7 of the drawings. As shaft 94 is continuously rotating, worm 120, worm wheel 121 and the clutch plate 123 will be continuously rotated. It will thus be seen that when the roller 132 on standard 133 comes into engagement with the shoe 131, the lever 130 is pivoted at the point 129 to shift the shaft 128 downwardly an amount sufficient to bring the clutch plate 124 into engagement with the clutch plate 123. The standard 133 is mounted on the lever 106 in such manner that the engagement of the two clutch plates 123 and 124 takes place at the same time that the feed rollers 7 and 8 are closed by the projection 113 on lever 111 and begin the feed of the wire to the forming die. As the clutch plate 123 through shaft 94, worm 120 and worm wheel 121 is continuously rotating, the closing of the two clutch plates 123 and 124 will start shaft 128 to rotating.

The clutch plate 124 is provided on its upper peripheral surface portion with a circular slot 134 (see Figs. 7 and 9) which is T-shaped in cross-section and within which is slidably positioned the head of a T-bolt 135 which threadedly carries a button or knob 135. The T-bolt 135 and the button or knob 135 may be shifted in the T-slot 134 to any desired position by first unscrewing the button 135 and then manually moving such elements. When once properly adjusted, however, such parts are fixedly secured in position with respect to the T-slot by screwing the button 135 down against the upper surface of the clutch plate 124. The position of the bolt 135 and button 135 will be determined by the length of time that the feed rollers 7 and 8 are to remain in cooperative relation. In the rotative movement of the clutch plate 124, the button 135 is moved in a counterclockwise direction, as viewed in Fig. 7 of the drawings, and is brought into engagement with the outer end of a free swinging arm 136 (see Fig. 7) which is rotatably mounted at its other end on the shaft 128. The free swinging arm 136 is connected to the lever 107 by means of a link 137 which is connected at one end to the outer end of such

free swinging arm and at its other end to the outer end of an extension 138 provided on the lever 107. Thus the bearing of the button 135 on the free swinging arm 136 causes the latter to be rotated in a counterclockwise direction, as viewed in Fig. 7 of the drawings, to cause the link 137 to be shifted to the left, as viewed in such figure, and thereby to cause the lever 107 to be rotated in a counterclockwise manner about its pivot 108 back towards its normal or starting position. The free end of the lever 107 has connected at a point adjacent to the universal connection 106 and preferably to such connection, as is illustrated in Figs. 7 and 9 of the drawings, one end of a spring 139 which is connected at its other end to the free end of the lever 111. By this arrangement the spring 139 is disposed on one side of the pivot point 108 of the lever 107 in the normal starting positions of the levers 107 and 111. When, however, the lever 107 is swung in a clockwise direction to the dotted line position shown in Fig. 7 of the drawings, in the manner heretofore explained, the spring 139 is likewise swung in the same direction so that it is positioned on the other side of the pivot point 108 and in this position, the spring is stretched and under increased tension. Thus as the lever 107 is returning to its normal position under the influence of link 137, free swinging arm 136 and button 135, the spring 139, as soon as it has been carried back past the pivot 108, will operate with a snap action to bring the lever 107 immediately back to its normal starting position. As a result of this action, there is an immediate release of the pressure exerted by the cam roller 109 on the free end of the lever 111, thereby enabling the lever 111 to return to its normal starting position. In returning to its starting position the lever 111 in turn withdraws the cam projection 113, thereby releasing the latter's pressure on the block 114 and enabling the spring 116 to shift such block to the right, as viewed in Figs. 7 and 8 of the drawings. The shifting of block 114 by spring 116 disconnects the two feed rollers 7 and 8 from their driving relation and renders them ineffective to continue the feed of the wire to the forming die 10.

The return movement of the lever 107 also causes the roller 132 to ride off the entry end of the shoe 131, thereby enabling the free end of the lever 130 to drop back to its normal position by its own weight. The restoring of the lever 130 to its normal position causes the other end thereof to shift the shaft 128 to break the driving connection between the clutch plates 124 and 123. Secured to the shaft 128 intermediate the two spaced bearing arms provided on the bracket 126, is a spool 127 provided with a spiral spring which is so attached to the bracket 126 that it is wound up as the clutch plate 124 is rotated in a counterclockwise direction, as viewed in Fig. 7 of the drawings, during the period of feed of the rollers 7 and 8. When the clutch plate 124 is released from clutch plate 123, however, the tensioned spiral spring immediately returns the clutch plate 124 and consequently the button 135 to their starting positions in position for the commencement of a new cycle of operations, such as has been hereinabove described.

When the shaft 59 has rotated through the first 90° of its revolution the cam 73 has been rotated to a position where the cam roller 95 and consequently the link 96 have been permitted to drop back to their normal positions, as has been pre-

viously explained. At the end of this portion of the cycle of the shaft 59, the lug 53 has come into engagement with the second wedge 51' (see Fig. 15) which retracts the lug 53 against the tension of its spring 55, thereby removing the pin 54 from the recess 57 with which it was engaged in the female clutch member 56 and disconnecting the shaft 59 from its driven relation with the motor 60. This operation takes place at the same time that the feeding rolls 7 and 8 have started the feed of the wire to the forming die 10 and shaft 59 will remain disconnected from the motor 60 throughout the entire period of feed of the feeding rollers 7 and 8 and until the lever 107 has been returned to its normal or starting position by the metering mechanism above described. When the lever 107 has been returned to its normal position, mechanism comes into operation to withdraw the wedge 51' from the path of the lug 53, thereby enabling the pin 54 to enter into engagement with a recess 57 on the female clutch member 56 and again drivingly connect the shaft 59 to the motor 60. The shaft 59 then continues its rotative movement through the remaining 270° of its cycle, at the end of which the lug 53 will again come into engagement with wedge 51 to disconnect such shaft from the motor 60. During the last 270° movement of the shaft 59, the cutter-elevating cam 72 comes into operation to lift the cutting mechanism into position to cut the ends of the wire, the cutter-operating cam 71 causes such cutting mechanism to operate and cut the wires and at the same time to bend the cut ends thereof and the clamp operating cams 70, 70 come into operation to lift the clamp member 36 from the top of the book so as to enable the operator to remove the same and place a new book in position for the next cycle of operations of the machine.

The mechanism for again connecting the shaft 59 with the motor 60 to enable the aforesaid operations to be accomplished by the cams 70, 70, 71 and 72, includes a swivel arm 140 which is pivoted at 140' to the gear housing 64 and carries at its outer end the wedge 51', as is shown more clearly in Fig. 16 of the drawings. The outer end of the arm 140 is also connected by a link 141 to a lever 142 which is pivoted intermediate its ends on a bracket 143 positioned on the top of the gear housing 64. The lever 142 is normally maintained to position wedge 51' in the path of the lug 53 by a spring 144 mounted in a seat provided in bracket 143. Pivotal movement of the lever 142 against the tension of spring 144 to remove the wedge 51' from the path of the lug 53, is accomplished by means of a shoe 145 (see Fig. 8) which is provided on the other end of the lever 142 and is adapted to be engaged and depressed by a roller 146 provided on the under side of the link 105 when such link is moved rearwardly to its normal position as the lever 107 is being returned to its normal position by the spring 139. The roller 146 is spring-pressed so that in the forward motion of the lever 105 the head thereof engages with a cam surface provided on the shoe 145 and is forced rearwardly against the tension of such spring until the roller clears the shoe 145 at the end of the forward movement of the link 105, the shoe 145 being so constructed that on the rearward movement of the link 105, the roller 146 comes into engagement with the top, outer surface of the shoe 145 to depress the same, as has been previously explained. As has been before mentioned, the removal of the wedge 51' enables the pin 54 to come into engagement with the re-

cess 57 and thereby connect the shaft 59 to the motor 60. As shaft 59 rotates, the cutter-elevating cam 72 shifts a link 147 (see Fig. 3) lengthwise through the medium of the cam roller 148 mounted on such link. The link 147 is provided with a fork-shaped end which straddles the shaft 59 intermediate the cam 72 and the gear housing 64 and at its other end, is connected to a bar 152 which is supported on the outer ends of two rocker arms 149, 149. The other ends of the rocker arms 149, 149 are secured to a rocker shaft 153 which is rotatably supported in the bearing brackets 150, 150 connected to the side frames of the machine, as is shown more clearly in Fig. 1 of the drawings. Fixedly connected to the bar 152 are a plurality of spaced links designated 151, which extend upwardly from the bar 152 and are connected at their upper ends to the under side of a shelf 154. Movement of the shelf 154 is confined to a vertical direction by means of two end guides 155, 155 which are recessed to receive tongue projections provided on the outer ends of the shelf 154. It will therefore be seen that as the cam 72 is rotated, the link 147 is shifted longitudinally in an upward direction through its connection with the cam by means of the cam roller 148, thereby causing the bar 152 and the rocker arms 149 to be rotated in a counter-clockwise direction, as viewed in Fig. 3 of the drawings, thereby raising the links 151 to lift the shelf 154 from its lowermost position up in the guides 155. As the shelf 154 is being raised, it raises a pair of cutting and bending units which are indicated generally in Figs. 1 and 3 by the reference character 156 and are slidably mounted on the frame of the machine, as will be hereinafter more fully explained.

The cam 72 is provided with a surface portion 72' which is concentric with the shaft 59 and causes the shelf 154 to dwell or be maintained in its uppermost position for a predetermined period as the shaft 59 and the cam 72 are being rotated. During this period of dwell the cam 71 comes into operation to actuate the cutting and bending devices 156 to cut the formed spiral wire and immediately following to bend the ends of the wire inwardly, thereby completing the formation of the spiral binding wire and locking the spiral against rotation and removal from the book.

The cam 71 is engaged by a cam roller 157 (see Fig. 3) which is mounted on an arm 158 intermediate the ends of the latter. The arm 158 is pivotally connected at one end to a lug 159 provided on the gear housing 64 and is connected at its other end to the lower end of a substantially vertically disposed link 160. The upper end of link 160 is connected to the outer forward end of an arm 161 fixedly secured to a square-shaped bar 162 extending lengthwise of the machine. The ends of the bar 162 are cylindrically formed and are rotatably mounted in suitable bearings carried by the frame of the machine. Intermediate the ends of the bar 162 are a pair of adjustable levers 163 (see Figs. 3 and 4) which extend rearwardly of the machine so that their outer ends are positioned above the shelf 154. The levers 163 are spaced apart a distance approximately equal to the width of the book to be bound. It will thus be seen that as the cam 71 approaches its high point during the period of dwell of the shelf 154, the arm 158 is rotated upwardly about its pivot 159 to raise the link 160, in turn to pivot the arm 161 upwardly and cause the shaft 162 to turn in a counter-clockwise direction, as viewed in Fig. 3 of the drawings, and

thereby depress the outer ends of the fingers or levers 163, which during such downwardly movement actuate the cutting mechanisms 156 associated therewith.

The cutting devices 156, as will be seen more clearly in Figs. 12 to 14 of the drawings, include a body portion 165 having on its forward face a dove-tailed slot 166 which extends transversely to the shelf 154 and inclines from the vertical at an angle corresponding to the pitch angle of the spiral. Slidably mounted in the slot 166 is a dove-tailed shaped block 167, with which is integrally formed a slide block portion 168 extending transversely to the block 167 so that they form a distorted cross-shaped member. The portion 168 of such member is slidably mounted in a longitudinally extending guideway 169 formed in a depending portion 170 (see Fig. 11) provided along the rear edge of the work-table. Thus the cutting unit 156 may be shifted lengthwise of the table by moving the block portion 168 in the guideway 169 and the body portion 165 thereof may be moved in an inclined transverse direction by moving said body and consequently the guideway 166 thereof relative to the block portion 167. One of the cutting devices 156 is positioned at each end of the binding edge of the book and when properly positioned for the operations to be performed are secured in such position by any suitable means such as the set screws 171. The upward inclined movement of the body portions of such units to bring the cutting and bending instrumentalities carried thereby into operative relation with the spiral binder threaded into the book, is brought about by the engagement of the shelf 154 with the heads of adjustable push screws 165', 165" threadedly received in the bottom ends of the body portions 165, 165' of such units, as is clearly shown in Fig. 11 of the drawings.

Integrally formed with the upper end of the body 165 of each unit is an angularly disposed member or extension 30 which is substantially parallel to the longitudinal center line of the slot 166. The extension or member 30 is substantially triangularly-shaped in cross-section, the wedge-shaped forward face of which is adapted to enter between the coils of the spiral in the upward movement of the body 165 of the cutting device 156 under the action of the shelf 154 so as not to disturb the portions of the spiraled wire which extend or protrude rearwardly from the binding edge of the book.

At the other end of the upper portion of the body 165 of each of the cutting devices, is provided an upwardly extending extension 181 which is provided on its forward face with a pair of guide members 179 and 180 adapted to pass on either side of one coil of the wire in the upward movement of the body 165 of the cutting device. The upper ends of the members 179 and 180 are beveled or flared to permit the ready access of the coil between such members and the bodies of such members are spaced apart a distance slightly in excess of the diameter of the wire so that the coil of wire fits readily therebetween without any excess play. At the end of the upward movement of the body 165 of the device, the two members 179 and 180 are positioned adjacent the upper end of the spiral coil with the top portion of the coil disposed between such members, the bottom ends of such members being positioned at a point above the axis of the spiral coil, as is shown in Fig. 13 of the drawings. Positioned directly below the member 180 and fixedly

secured to the body 165 of the device, as by means of set screws 174, is the stationary blade 173 of a cutting device. The fixed blade 173 and the guide member 180 are aligned and extend at an angle substantially equal to the pitch angle of the spiral coil. Associated with the fixed blade 173 of the cutting device and normally positioned beneath the guide member 179 is a movable blade 175 integrally formed on the upper end of an arm 176 which is integrally formed with a bearing portion 176' extending through an aperture in the body 165 of the device and rotatably supported in such aperture. The rear end of the portion 176' projects outwardly beyond the rear surface of the body 165 of the device and has secured thereto one end of an arm 177, which extends along the rear upper portion of the device and at its free end projects outwardly from a side thereof. The arm 177 is normally maintained in its uppermost position, as is illustrated in Figs. 13 and 14 of the drawings, by means of a coiled spring 182 which is positioned intermediate the outer end of such arm and a projection formed on the rear of the unit. Pivoted connected to the outer free end of the arm 177 is an elongated depending ring 178 through which extends the outer end of a lever 163 (see Figs. 3 and 11).

It will be evident from the foregoing that when the lever 163 is pivoted downwardly by the shaft 162, the free end thereof engages with the lower end of the elongated ring member 178 and forces such ring member downwardly, thereby causing the arm 177 to pivot the movable blade 175 toward the fixed blade 173 and thereby cut the portion of the spiral extending between the cutting surfaces of such blades. As the blade 175 continues its movement between the fixed blade 173 and the guide member or anvil 180, the portion of the wire immediately above the point of severance is bent about the lower left-hand edge of the anvil 180, as viewed in Fig. 13 of the drawings, and extended inwardly toward the adjacent coils on the book so as to be positioned substantially parallel to the axis of the spiral wire, as is indicated by the dotted line end portion designated 1' in Fig. 5 of the drawings.

The two cutting devices 156, 156' are substantially similar in construction except that in the right-hand device, as viewed in Fig. 4 of the drawings, the movable blade is positioned to wipe over the upper end of the fixed cutting blade, as is illustrated in Fig. 13 of the drawings, so that the inwardly projecting bent portion is connected to an upwardly rising portion of the coil (note the dotted portion designated 1' in Fig. 5 of the drawings). The cutting device on the left-hand side of the machine, as viewed in Fig. 4 of the drawings, has the cutting and bending devices reversed, that is, the two bending members are positioned below the cutting members and their positions with respect to the body 165 are interchanged. This is illustrated in Fig. 15 of the drawings, the bending members 179' and 180' in such figure corresponding to the bending members 179 and 180, respectively, shown in Fig. 13 of the drawings and the cutting members 173' and 175' in such figure corresponding to the cutting members 173 and 175, respectively, shown in Fig. 13 of the drawings. Referring more particularly to Fig. 15 of the drawings, it will be seen that the bending member 180' is positioned below but in alignment with the fixed cutting blade 173', while the bending member 179' is positioned below and in alignment with the movable cutting

blade 175'. It will also be noted that the members are so arranged that the cutting blade 175' will move in a counter-clockwise manner, as viewed in such figure, instead of in a clockwise manner as does the cutting blade 175 shown in Fig. 13 of the drawings, and will, therefore, cut and bend the wire in a direction directly opposed to that of unit shown in Fig. 13, so that at the end of the cutting and bending operations the two cut bent ends of the wire will be positioned within the ends of the spiral member and will extend towards each other. By the time that these operations have taken place, the cam roller 148 will have traversed the cam portion 72', thereby ending the period of dwell and enabling the shelf 154 to fall by its own weight. The body 165 of each cutting unit 156, however, is held in its elevated position by means of a friction spring 183 (see Fig. 12) which is positioned in a recess provided in the inner face of the guide portion 167 and bears against the adjacent face of the body 165 of the cutting device.

Following the cutting and bending operations above described, the two identical cams 70, 70 mounted on the ends of shaft 59 cause the book clamp 34 to be lifted through their engagement with cam rollers provided on two spaced lever arms 190 secured at their ends to a bar or shaft 191 extending longitudinally of the machine and rotatably mounted in the bearing brackets 192. As is shown more clearly in Fig. 2 of the drawings, the rear or free end of each of the levers 190 is normally urged downwardly by means of a tension spring 194 connected at its upper end to the free end of its associated lever 190 through a depending link 193 and connected at its lower end to an adjustable anchorage 195 provided on the frame of the machine. The free ends of the levers 190 are also connected to the lower ends of substantially vertically disposed links 196, which at their upper ends are pivotally connected to bearing pins 197 provided on each end of the body 34 of the clamp. It will thus be seen that as the free ends of the levers 190 are pivoted upwardly by the cams 70, 70, the links 196 are raised against the tension of their associated springs 194 to lift the clamp body 34 to a position where the spring-pressed holding members 33, 33 provided on such body are enabled to move outwardly under the tension of their associated springs and come into engagement with the tops of the guides 35, 35 which slidably support the clamp body and thereby releasably hold the clamp body in its elevated position. On the continued rotation of the shaft 59 the elevated portions of the cams 70, 70 pass the rollers associated with the lever arms 190 so that when the spring-pressed members 33, 33 are pressed by the threaded bolts 31, 31, as has been previously explained, the released clamp body 34 and its associated mechanism is free to drop to a position determined by the thickness of the book D placed on the table.

Also raised with the clamp body 34 is a dampening and guide bar 198 (see Figs. 5 and 6) which is loosely pivoted to the foot of the clamp by means of the two integrally formed end arms 199, 199. When the clamp body 34 is released by depressing the spring-pressed pins 33, 33 the dampening or cushioning bar 198 falls into position on top of the binding edge of the book, beyond the series of perforations provided therein and in position to overlie a portion of the spiral binder as it is being fed through the book. The cushioning member 198 is provided with a series of slots 197 which are offset to the same degree 75 pivot 205 in a counter-clockwise direction, as

as the pitch angle of the spiral and are sufficiently deep so that the spiral as it is being fed through the book does not come into contact with the interior surfaces of such slots but rides freely therethrough. The slots are chamfered or belled at the rear to permit the leading end or tip of the binding coil to freely enter such slots progressively as it is being fed through the aligned perforations of the book. The member 198 will remain in this position on the binding edge of the book until the cutting and bending units 156, 156 are raised by the shelf 154, at which time the guide portions 30, 30 of such units will engage the member 198 and tilt it upwardly about its arms 199. The dampening member 198 remains resting in this tilted position on the guide members 30, 30 of the cutting units until the clamp has been raised, whereupon it will be free to fall back to a horizontal position.

The machine also includes a side gauge 211 (see Fig. 2) for correctly positioning the book on the table so that the sets of apertures thereof will be in proper position to receive the hooked fingers 29 when the handle A is thrown forwardly by the operator. The side gauge 211 is controlled by the operating handle A through an actuating arm 200 (see Fig. 20) which is secured at its upper end to the bearing bracket 20 associated with the handle unit. The lower depending end of the arm 200 engages the upper end of a rocker lever 201 which is rotatably mounted on shaft 153, the lower end of such rocker arm being connected to one end of a link 202 which is pivotally connected at its other end to an offset portion or arm 203 of a bell crank 205. The bell crank 205 is pivotally connected to the frame of the machine at 204. The other arm of the bell crank lever is connected to the lower end of an adjustable rod 206 which extends up through a bracket 207 secured to the frame of the machine and is provided at its upper end with a universal joint 209 which connects such end of the rod with one arm 210 of a bell crank lever. On the rod 206, intermediate the bracket 207 and the universal joint 209, is provided a spiral spring 208 adapted to normally maintain the rod 206 and consequently the above mentioned connected parts in the position illustrated in Fig. 20 of the drawings. The bell crank 210 is pivotally mounted at 211 on a bracket 212 mounted on the frame of the machine (see Fig. 21). Arm 213 of the bell crank lever 210 extends upwardly and is provided on its free end with a roller 214 which is positioned in a recess provided on the under side of a block 215. The block 215 extends through a slot 220 provided in the table 221 and at its upper end, which is reduced in cross-section, it extends through a slide plate 216. The slide plate 216 is mounted for longitudinal movement in a pair of ways or angle plates 218 (see Fig. 20) which form guides for the slidable member 216. The forward end of the slide 216 bears the feed gauge plate 217.

From the foregoing, it will be seen that as the operating handle A is initially pivoted forwardly, the arm 200 carried on by bearing bracket 20 will engage the upper end of the loosely supported rocker lever 201 and cause the lever to be rotated in a counter-clockwise manner, as viewed in Fig. 20 of the drawings, to shift the link 202 connected with the lower end of such rocker arm forwardly or to the right, as is shown in Fig. 22 of the drawings. The forward movement of the link 202 pivots the bell crank lever 205 about its pivot 204 in a counter-clockwise direction, as

viewed in Figs. 20 and 22 of the drawings, throwing it to the position illustrated in Fig. 22 where it will be locked in dead center position until displaced therefrom, as will be hereinafter explained. The pivotal movement of bell crank lever 205, causes the rod 206 to be drawn downwardly against the tension of spring 208, thereby causing arm 210 of the bell crank lever connected by the universal joint 209 to the upper end of link 206, to be pivoted downwardly about its pivot 211. The downward movement of arm 210 causes the arm 213 connected thereto, through the roller 214, to withdraw the block 215 and slide 216. The gauge plate 217 mounted on the inner end of slide 216 is thereby withdrawn from the adjacent edge 222 of the table 23 of the machine. When a book is placed on the table 23 the gauge plate 217 is in its fully advanced position at a predetermined distance from the edge 222 of the table. This distance between the two parts may be adjusted by turning the gauge screw 223 so that the apertures of the book to be bound will be in proper position to readily receive the ends of the hooked fingers 29 when the operating handle is pivoted forwardly by the operator. The forward movement of the operating handle A withdraws the gauge plate 217 from the book just prior to the entry of the hooks 29 into the apertures of the books, the distance of withdrawal of the gauge plate 217 being preferably at least as great as the pitch between adjacent coils of the binder to enable the hooks 29 to shift the pages of the book in a sidewise manner without interference in the formation of the apertures of the book to segments of helical form, as has been previously explained. The positions to which the above described parts have been actuated by the forward throw of the handle A, are maintained throughout the feeding of the spiral wire and the cutting and bending of the ends of such wire.

Provided on the rocker lever 201 is a pin 225 which is adapted to be engaged by a slot provided on a latch member 226 which is pivotally supported intermediate its ends on a rocker arm 227 secured to the shelf-operating shaft 153. The latch 226 is normally urged toward a stop pin 228 by means of a spring 229 which is connected at one end to the latch 226 intermediate the pin 228 and its point of pivotal connection with the arm 229 and at its other end is connected to an extension 230 secured to the shaft 153. The normal position of the rocker arm 201 with the latch and latch-operating mechanism above described is illustrated in Fig. 20 of the drawings. When the rocker arm 201 is pivoted in a counter-clockwise direction to withdraw the gauge plate 217, as has been hereinabove explained, the pin 225 has been shifted to the left to the position illustrated in Fig. 22 of the drawings, the pin and the rocker arm 201 carrying it being maintained in such position due to the fact that the bell crank 205 is locked on dead center, as has been previously explained. When the shaft 153 is rotated to lift the shelf 154, the arm 227 is rotated in a counter-clockwise direction, as viewed in Fig. 20 of the drawings, to bring the recess of the latch 226 into engagement with the pin 225, thereby positioning these parts so that when the cutting and bending operations on the spiral binder have been finished, the parts are set to be tripped, as is illustrated in Fig. 22 of the drawings. When the shelf 154 is returning to its lowermost position the arm 227, through the shaft 153, is caused to rotate in a clockwise di-

rection, as viewed in Fig. 22 of the drawings, and through the connection of the latch 226 with the pin 225 forces the rocker lever 201 in a clockwise direction about the shaft 153. The bell crank lever 205 through the link connection 202 with rocker lever 201 is thus rotated in a clockwise direction, to bring the pivotal connection of arm 206 with said bell crank lever past dead center, whereupon the tensioned spring 208 comes into operation to snap the arm 206 upwardly, thereby restoring gauge plate 217 through bell crank lever 210, block 215 and slide 216 to its normal advanced position with respect to edge 222 of the table 23. The gauge plate 217 is by this action restored to a position for reception of a new book or pages to be bound, such book or pages being placed by the operator up against the front face of the plate 217.

Adjustment of the rear portion of the work table 23 in a vertical direction is attained through adjustment of a knurled thumb wheel 234 which is secured to a shaft 235 extending across the entire width of the table along the rear end portion thereof (see Fig. 17). The shaft 235 has secured thereto, at spaced points, a pair of worms 233 which engage with worm wheels 232 contained in recesses provided on the rear edge portion of the table 23. The worm wheels 232 are mounted on a pair of supporting pins 230 (see Figs. 17 and 18) which depend downwardly below the table and rest upon a fixed portion 231 of the frame. The bores of the worm wheels 232 are provided with screw-threads which threadedly engage threads provided on the pins 230. Thus as the thumb wheel 234 is adjusted, the rotational movement imparted to the worm wheels 232 causes the supporting pins 230 to shift lengthwise along the axis of rotation of the worm wheels 232. The pins 230 are provided with longitudinally extending slots 236 within each of which projects a pin member 237 secured to the table and through such connection preventing the pins 230 from rotating with the worm wheels 232. It will thus be seen that by manipulating the thumb wheel 234 the rear end of the work table may be adjusted with respect to the fixed portion 231 of the frame in a substantially vertical direction. The rear end of the table should preferably be adjusted to a position so that when a book is to be bound with a spiral binder of a predetermined diameter, the center of the book along a line extending through the centers of the series or sets of apertures, as for example, the line indicated by the numeral 238 shown in Figs. 5 and 6 of the drawings, shall be approximately similar to the axis of the spiral binder when fed into position on the book.

The table 23 is positioned intermediate two fixed table portions 243, 243 and, as is shown more clearly in Fig. 23 of the drawings, is pivotally connected to such fixed portions at its forward end by means of a pair of pins 241, 241 which project from extensions 240, 240 provided on the side forward ends of the table 23 and extend into slots 242, 242 of a pair of blocks 244 at the forward ends of the fixed table portions 243, 243.

The blocks 244, 244 are made of hardened metal and are inserted in recesses provided in the forward ends of the fixed table portions 243, 243 adjacent to the forward end of the table 23. The slots 242, 242 in the blocks 244, 244 extend lengthwise of the table portions 243, 243 and permit movement of the pins 241, 241 relative thereto to enable the table 23 to be shifted towards and away from the axis of the spiral die 10. Interme-

diate the ends of the table 23 and on the under side of the forward portion thereof are provided a pair of depending lugs 246 and 247 between which is positioned a yoke 248 which is pivotally supported in the lugs 246, 247 by means of pins. Extending through the body of the yoke 248, fixedly secured to the latter in any suitable fashion, is the end of a stem 249 of an adjustment member, such stem extending also through and being threadedly engaged with a block 250 which is secured to a fixed portion of the machine, as for example, the cross-beam or bar 251 which is integrally formed with the fixed portions 243, 243 of the table and extends across the front of the machine. On the outer end of the stem 249 is provided a hand-wheel 252 which, when rotated to rotate the stem 249, causes variations in adjustment as between the block 250 and the yoke 248 and consequently causes adjustment of the table in a forwardly or rearwardly direction with respect to the stem 249. As has been previously explained, the pins 241, 241 pivotally supporting the ends of the table are slidably mounted in the guide blocks 242, 241 so that such adjustment of the table may be readily accomplished. Preferably a lock nut 253 having a handle portion 254 is interposed between the hand-wheel 252 and the block 250 so that the operator by turning the hand lever 254 may lock the table in its adjusted position.

Projecting from each side of the rear portion of the stationary table portions 243, 243 are a pair of brackets 255, 255 (see Fig. 2) through each of which extends an adjustable member 256 normally secured in fixed position with relation to its associated bracket 255 as by means of a lock nut. The members 256 each have an enlarged head adapted to be engaged by the shell or housing E and which serve as surface supports for the shell E when the operating handle A is moved rearwardly to bring the spiral feeding and bending mechanism into operation. The contact surfaces of the heads of members 256 may be coated with rubber or otherwise finished to reduce the wear and friction of the housing member E on such members to a minimum.

Mounted on shaft 25 of the handle unit so as to be concentric to the hooked fingers 29, is an arcuately-shaped plate 260 (see Figs. 1, 3, 10 and 19) which moves in unison with the hooks 29 when the operating handle A is actuated. Positioned on the frame of the machine is an electrical switch 261 (see Figs. 1 and 19) which normally is not engaged by the arcuately-shaped member 260 in the normal operations of the machine. Should the hooks 29, however, fail to properly enter the apertures in the book due to misplacement of the book, or any other reason, shaft 25 is displaced from its normal position, thereby disturbing the concentric relation of the arcuately-shaped member 260 with the axis of the feeding die and causing such member to engage the electrical switch 261 so as to close the same. The switch 261 is contained in a circuit which includes a solenoid 262 (see Figs. 7 and 8) connected to and controlling the position of shaft 101 and the enlarged key portion 104 thereof which is positioned intermediate the recessed hubs of the levers 100 and 103. The solenoid 262 is connected to the shaft 101 through a lever 263 which is pivotally supported intermediate its ends on a bearing bracket 264 secured to a fixed portion of the machine. It will thus be seen that when switch 261 is actuated as a result of the inability of the hooks to properly enter the apertures in the book,

the solenoid 262 is actuated to withdraw the shaft 101 from its normal position, thereby withdrawing the enlarged key portion 104 thereof from the recess in the lever 103 and consequently destroying the rigid bell crank relationship between the levers 100 and 103. Thus when link 96 and lever 100 are actuated by cam 73, such motion is not transmitted to lever 103 due to the destruction of the operative connection between levers 100 and 103 and the mechanism which would ordinarily operate the feed rollers to feed the wire are maintained in static condition so that the cycle of operations of the machine is completed without feeding the wire through the book. Attached to the free end of the lever 263 is a roller 265 which bears against and controls the movement of a link 266 which is connected at one end to wedge 51' and at its other end is provided with a slot 267 adapted to engage with a pin 268 provided on push rod or link 96. Normally the connection between the link 96 and wedge 51' is broken due to the fact that recess 267 does not engage pin 268 but is spaced from such pin, as is illustrated in Fig. 8 of the drawings. When, however, the solenoid 262 is actuated to force the lever 263 in a clockwise direction about its pivot 264, as viewed in Fig. 8 of the drawings, the wheel 265 on the outer end of lever 263 gives way to permit the recess 267 to come into engagement with and lock on the projection or pin 268. The lever 96 is then connected to the wedge 51' so that as link 96 is actuated by cam 73, link 266 is caused to withdraw wedge 51' from its normal locking position with respect to the lug 53, thereby enabling pin 54 to come into engagement with the recess on the female member 56 of the clutch and drivingly connect the shaft 59 with the motor 60 and permitting the machine to continue and complete its cycle of movements without, however, as has been previously explained, permitting the spiral wire to be fed to the book.

When the solenoid 262 is actuated, means come into operation to restore the normal position of shaft 101 with respect to levers 100 and 103, so that as succeeding books are placed on the machine the latter may function in a normal manner. The means for accomplishing this includes a bell crank lever 270 which is pivotally supported at 271 on a fixed portion of the machine and has an arm 272 which is connected to the armature 273 of the solenoid by means of a link 274. The outer end of the bell crank arm 272 controls a switch 275 which is opened when the solenoid 262 is operated as a result of the switch 261 being closed, thus breaking the circuit in which the solenoid 262 is included. The rotative movement imparted to the bell crank lever 270 causes the arm 272 thereof to be moved downwardly into the path of movement of a pin 277 on push rod 160 which is connected to cam 71 through lever 158 and cam roller 151, as is shown in Fig. 3 of the drawings. Thus as push rod 160 is shifted upwardly during the completion of the machine cycle, the projection 277 engages the arm 272 of bell crank lever 270 and pivots such bell crank lever about its pivotal point 271 to bring it to its normal position, the plunger 273 of the solenoid 262, lever 263 and shaft 101, together with the enlarged key portion 104 being returned to their normal positions so that such several parts condition the machine for its usual normal cycle of operations.

It will be understood from the foregoing description that when the machine is in operation and ready to receive a book to be bound, the

operating handle A is in the position illustrated in Figs. 2, 3 and 10 of the drawings. The body portions 165 of the cutting and bending units 156 and consequently the guide members 30 formed thereon are in their uppermost position, as is illustrated in Fig. 10 of the drawings, and the side guide plate 217 is in its fully advanced position. The motor 60 is in operation and is constantly rotating the feed rollers 1 and 8 and the clutch plate 123 of the metering mechanism, as has been previously described. The clamp member 34 is being held in its inoperative raised condition by the spring-pressed plungers 33 which are resting on the upper surfaces of the clamp guides 35-35, as is illustrated in Fig. 1 of the drawings. With the mechanisms of the machine so conditioned, the operator places a book of unbound sheets on the table 23 of the machine so that its rear perforated binding edge is placed up against two guide members 30, 30 of the cutting and bending units 156 and one side edge is placed against the side guide member 217. The book of sheets will thus be positioned so that the apertures thereof will be enabled to readily receive the ends of the hooked fingers 29 when the operating handle is moved forwardly by the operator. The operator then grasps the handle A and throws it to a forward position. During the initial forward movement of the handle A, the forward edge of the plate 27, on which are mounted the hooked members 29, engages with the portions 181, 181' of the two cutting and bending units 156, 156 to depress the body portions 165, 165 of such units against the frictional pressure of their associated springs 183 to such an extent that the heads of the bolts 165' thereon are brought into engagement with the upper surfaces of the actuating shelf 154. At the same time the arm 200, carried by the bearing bracket 28, engages the upper end of the loosely supported rocker lever 201 and causes the lever to be rotated in a counter-clockwise manner, as viewed in Fig. 20 of the drawings, to shift the link 202 connected with the lower end of such rocker end forwardly or to the right, as is shown in Fig. 22 of the drawings, until the arm of the bell crank lever 205 to which the adjustable rod 208 is connected is moved to a dead center position. During this movement of the bell crank lever 205, the arm 206 is drawn downwardly against the tension of spring 208, thereby causing through the associated mechanism the withdrawal of the side gauge plate 217 to a retracted position, away from the book placed on the table. With the guide members 30, 30 and 217 removed, the book is in a condition whereby the pages thereof may be shifted by the hooks 29 without any interference. Just subsequent to the removal of these guide members, as the handle A is moving forwardly, the hooked fingers 29 enter the apertures along the binding edge portions of the book and while the handle A is moving from the position shown in full lines in Fig. 11 of the drawings to the position shown in dotted lines in such figure, such hooks shape each set of successive perforations so that it defines a passageway which conforms in curvature to the curved portion or segment of the helical binder which will extend therethrough. Just prior to the arrival of the handle A to the dotted line position shown in Fig. 11 of the drawings, the threaded clamp operating members 31, 31 engage with the spring-pressed plungers 33, 33 of the clamp 34 and force them forwardly against the tension of their associated springs. When the handle has reached the dotted

line position shown in Fig. 11 of the drawings, the spring-pressed plungers have been retracted sufficiently to clear the upper surfaces of the guides 35, 35, the clamp 34 then dropping under its own weight so that the shoe 36 comes to rest on the top page of the book with the slots 45 on the rear projecting edge of such shoe positioned so that the projecting portions or teeth formed by the slots will be positioned intermediate the sets of apertures formed in the binding edge of the book. As the apertures 45 are aligned with the apertures 185 formed in the block 23' seated on the rear edge of table 23, the teeth formed by the slots 185 in such member 23' together with the teeth formed by the slots 45 in the shoe 36 thus firmly clamp together and afford a firm support for the binding edge portions of the sheets intermediate the apertures or perforations thereof. At the same time the bar 198 falls into position on top of the outer edge portion of the binding edge of the book beyond the series of perforations provided therein and in position to overlie a portion of the spiral binder as it is being fed through the book, as is shown more clearly in Figs. 5 and 6 of the drawings. The forward throw of the handle A thus removes the guiding means for the operator when he places the book upon the table, conditions or reshapes the book so that the perforations thereof will have the form desired for the feeding of the spiral binder thereto and firmly clamp the pages of the book in their reshaped condition. At this point it may be noted that the hooks 29, which are non-adjustable, are the focal points for all 10 adjustments on the machine. For instance, the side gauge 217 is adjusted so that when the book is placed on the table against such guide, the apertures in the book will be caused to register with the hooks 29. The slots 45 of the clamping 15 shoe 36 and the slots 185 in the block 23' at the rear of the table 23 are likewise in registry with the hooks 29. The adjustment of the rear of the table and also of its fore and after position is likewise made to insure registry of the hooks 29 20 with the apertures in the book and the proper formation of such apertures by the hooks 29. Thus when the book in its formed condition is clamped between the clamp shoe 36 and block 23', the apertures of the book and the several 25 coacting parts are in proper registry for the reception of the spiral wire to be fed into such apertures.

The operator next moves the handle A rearwardly to remove the hooks 29 from the apertures of the book. Inasmuch as the book is now clamped in position so that the interior surfaces of the apertures in the book are relatively fixed, the fingers 29 during their outward or returning movement are cammed in the direction of the pitch of the holes to shift the carriage, of which the handle A is a part, to one side against the tension of the spring 25, the latter immediately returning the carriage to its normal position after the hooks have cleared the apertures of 30 the book. The backward throw of the handle A causes also the operating arm 46 to engage the starting lever 47 which, when actuated, withdraws wedge 51 of the pin clutch mechanism 52 from the path of stop lug 53, thereby enabling spring-pressed pin 54 to come into engagement with a recess 57 of the female member 58 of clutch 52 and thereby connect the main cam shaft 59 in driven relation to the motor 60, in the manner previously described. During the 35 first 90° turn of the shaft 59 the feed roller con-

tro cam 73 comes into operation and causes the lever 107 to be rotated in a clockwise manner to the dotted line position shown in Fig. 7 of the drawings. As a result of this movement of the lever 107, the lever 111 is rotated to cause the projection 113 thereon to engage with and shift the slide block 114 against the pressure of its spring 116 an amount sufficient to bring the feed rollers 7 and 8 into cooperative relation to feed the wire toward the spiral forming die 10. At the same time the roller 132 provided on lever 107 comes into engagement with shoe 131 on the lever 130 to pivot such lever so that the clutch plate 124 comes into frictional engagement with the continuously rotating clutch plate 123, thereby starting the operation of the metering mechanism at the same time that the feed rollers 7 and 8 are rendered operative to feed the wire. The feed rollers 7 and 8 in their operative condition feed the wire 1 from the supply reel 2 into the die 10 where such wire is formed by the internal groove 12 (see Fig. 5) into a spiral shape and then fed to the spiral groove 17 of the pilot 16, which brings the wire to a point where it will be fed downwardly into the first perforation of the book immediately adjacent to the end of the pilot 16. As the feeding and forming of the wire is continued, the wire successively passes through the bell-shaped mouths of the slots 197 in the cushioning bar 198, then through the slots 45 of the clamp foot member 36, through the shaped apertures of the book and then out through the slots formed in the longitudinally extending bar 23' positioned along the rear edge of the table 23. It will be evident from Fig. 5 of the drawings that the wire enters the apertures of the book almost immediately after it leaves the pilot 16 so that the book itself forms in effect a continuation of the pilot 16, thereby reducing to a minimum vibration and whipping of the spiral wire during such feeding movement. Any possibility of the wire vibrating or whipping during such feed is obviated by the bar 198, which functions as a cushioning or dampening bar to eliminate such possibility. During the period of time that the formed spiral wire is being fed through the apertures of the book, the button or knob 135 of the metering device is moving in a counter-clockwise direction, as viewed in Fig. 7, until it is brought into engagement with the free swinging arm 136 and on such engagement the arm 136 is shifted in the same direction to cause link 137 to start the return movement of the lever 107. As soon as the spring 139 has been shifted past the pivot point 108 of lever 107 during the return movement of the latter, it comes into operation to return lever 107 to its normal position with a snap action. At the same time it returns the lever 111 to its normal position with a snap action, thereby almost instantaneously withdrawing projection 113 and enabling spring 116 to move guide block 114 to its normal position, thereby rendering the feed rollers 7 and 8 inoperative to further feed the wire. At the same time the roller 132 becomes disengaged from the shoe 131, thereby enabling lever 130 to drop to its normal at rest position by its own weight and consequently disengaging the two clutch plates 124 and 123 to stop the metering mechanism. The knob 135 upon such disengagement of the clutch plates will be immediately returned to its normal starting position through the action of its associated spiral spring.

The shaft 59 had completed the first 90° of its revolution at the time that the feed rollers 7 and 75

8 and the metering mechanism had been started and at the end of this portion of its cycle had been rendered inoperative by the lug 53 coming into engagement with the second wedge 51' of the pin clutch mechanism 52. During the return movement of lever 107, the roller 146 carried on link 105 engages shoe 145 on the outer end of lever 142 to depress the same against the pressure of its associated spring 144, thereby withdrawing the wedge 51' of the pin clutch 52 to permit the shaft 59 to continue its rotative movement. During the last 270° movement of the shaft 59, the cutter-elevating cam 72 comes into operation to lift the shelf 154 from the position shown in Fig. 11 of the drawings to a position where the bodies 165 of the cutting and bending units 156 are positioned, as illustrated in Figs. 3 and 10 of the drawings. During such lifting movement the guide members 30 of the units 156 pass in between the rear portions of the coils of the spiral binder and the members 179 and 180 of the cutting units pass on each side of the particular coils of the binder which are to be cut. During the period of dwell of the cam 72, while the shelf 154 is maintained in its uppermost position, the cutter-operating cam comes into operation to depress the actuating fingers 163 and thereby depress the levers 177 mounted on such units to actuate the movable cutting blades 175, 175' thereof, the cutting blades during their period of movement cooperating with the fixed blades 173, 173' to cut the end coils of the binder and cooperating with the members 180, 180' of such units to bend the cut ends of the binder so that they are directed inwardly within the binder and lock the latter in position in the book. It will be noted that due to the fact that the pilot 16 is cut away (see Fig. 5) to enable the portion 181 of the cutting and bending unit 156 at the right-hand end of the machine, as viewed in Fig. 4 of the drawings, to move upwardly without interference the spiral binder will be cut at a position closely adjacent to the outer end of the pilot 16 and will provide a new end in position to immediately enter the first aperture of a new book as soon as the feeding rollers 7 and 8 again come into operation. It will also be noted that during the raising of the body portions 165 of the cutting and bending units 156, the guide members 30, 30 thereof engage the bar 198 and lift it to an upward position out of the way of the cutting and bending mechanism. As soon as the movable cutting blades 175, 175' have completed their cutting stroke, the springs 182 associated with such units immediately return such blades to their normal starting positions.

By the time that the cutting and bending operations have taken place the period of dwell of the cam 72 will have come to an end, thereby enabling the shelf 154 to fall by its own weight. The body portion 165 of each cutting unit, however, is held in its elevated position by means of the friction springs 183. While the shelf 154 is returning to its lowermost position, the rocker arm 227 on shaft 153 is rotated in a direction to force the latch 226 and consequently the rocker lever 201 in a direction to shift the link 202 to bring the pivotal connection of the link or rod 206 with its associated bell crank lever 205 past dead center whereupon the tension spring 208 comes into operation to snap the link or rod 206 upwardly, thereby restoring gauge plate 217 to its normal advanced position.

Following the cutting and bending operations,

the two cams 17 also cause the book clamp 34 to be lifted in the manner previously described until the spring-pressed plunger members 33, 33 have again cleared the upper end of the clamp guides 35, 35 whereupon the springs associated with such members come into operation to advance them to a position where they can rest on the upper ends of the guides 35, 35 to retain the clamp 34 in lifted position.

It will thus be seen that as a result of these operations the parts have been restored to positions to start a new cycle of operations and as the shaft 59 has completed one complete rotation lug 53 again comes into contact with wedge 51 which causes the disruption of the driven relationship of shaft 59 with motor 60, thereby maintaining the parts in such positions until the handle A is again actuated by the operator. The series of operations of the machine are so extremely accurate and speedy that from 600 to 1,500 books, depending on the length of the binding edge and thickness of the books being bound, can be bound in an hour with practically no failures.

While in the foregoing I have described a preferred embodiment of my invention, it will be obvious to those skilled in the art that various modifications and changes may be made in the form, construction and arrangement of the several parts without departing from the spirit and scope of the invention and hence I do not wish to limit myself strictly to the structure herein set forth.

I claim:

1. A machine for binding books with helically-shaped binders and having, in combination, a table adapted to receive a book to be bound, binder forming means spaced from the portion of the table on which a book is to be placed and adapted to feed a helically-shaped binder toward a book on the table, a plurality of spaced, hooked-shaped positioning members adapted to enter into sets of successive apertures in the sheets of the book arranged in a row along the binding edge of the book and to shape each set of successive apertures into an arcuate form, said positioning members being offset to substantially the same degree as the pitch of the coils in the helical binder to be inserted so that the apertures in each set will define a passageway which substantially conforms in curvature to the curved portion of the helical binder which will extend therethrough, means operable to cause said members to enter into the apertures of the book for the forming operation and to withdraw such members after the apertures have been properly shaped, and means for feeding a helically-shaped binder through the thus shaped apertures after said positioning members have been withdrawn.

2. A machine for binding books with helically-shaped binders and having, in combination, a table adapted to receive a book to be bound, a plurality of spaced hooked-shaped members adapted to enter into sets of successive apertures in the sheets of the book arranged in a row along the binding edge of the book and to shape each set of successive apertures into an arcuate form, the aperture engaging portions of said members having an arcuate curvature determined by the diameter of the helical binder to be inserted in the book and being offset to substantially the same degree as the pitch of the coils in such helical binder, whereby said members will shape each set of successive perforations so that it defines a passageway which conforms in curvature to the curved portion of the helical binder which

will extend therethrough, means pivotally supporting said hook-shaped members, means operable to pivot said members into engagement with the apertures of the book and to withdraw them after the apertures have been properly shaped, and means for feeding a helically-shaped binder through the thus formed apertures.

3. A machine such as defined in claim 2, in which the means pivotally supporting the hook-shaped members is mounted for movement in an arcuate path after said members have entered the apertures of the book.

4. A machine such as defined in claim 2, in which the means pivotally supporting the hook-shaped members includes a rotatable shaft, a bracket secured to said shaft and supporting said members, and means pivotally supporting said shaft whereby said shaft, bracket and hooked-shaped members may be moved in an arcuate path.

5. A machine such as defined in claim 2, in which the means pivotally supporting the hook-shaped members is mounted for movement in a direction transversely to the path of pivotal movement of such members, and means yieldably resisting transverse movement of said means in one direction and adapted to retract said means at the end of the movement in such direction.

6. A machine for binding books with helically-shaped binders and having, in combination, a table adapted to receive a book having sets of successive apertures arranged in a row along the binding edge of the book, binder forming means spaced from the portion of the table on which a book is to be placed and adapted to feed a helically-shaped wire toward a book on the table, guide means associated with said table for positioning the book so that the apertures thereof overlie a predetermined portion of the table, aperture forming means including hook-shaped pivoted positioning members adapted to engage sets of successive apertures in the book and to shape the same so that they define passageways which substantially conform in curvature to the curved portions of the helical binder which will extend therethrough, means for clamping the book as thus formed on said table, means for withdrawing the aperture forming means from the thus formed and clamped book and means for feeding a helically-shaped binder through the thus shaped sets of apertures after said aperture forming means have been withdrawn.

7. A machine such as is defined in claim 6, in which said clamp includes a clamp shoe adapted to engage the binding edge portion of the book, said shoe being provided with a series of slots offset to substantially the same degree as the pitch of the coils in the spiral binder to be inserted, the teeth formed by such slots being adapted to engage the book intermediate the apertures thereof and to function as guides during the feed of the helical binder into the apertures of the book.

8. A machine such as defined in claim 6, in which said clamp includes a clamp body and a clamping shoe supported by said body, means for adjusting said clamping shoe in a transverse direction with respect to said body, and means for adjusting said shoe longitudinally of said body.

9. A machine such as defined in claim 6, in which said table in the region of the binding edge of the book is provided with a series of slots offset to substantially the same degree as the pitch of the coils in the helical binder to be

inserted and in which the book engaging portion of said clamp is provided with a series of slots adapted to register with the slots in said table, the teeth formed in said table and clamp by said slots coacting to securely clamp the binding edge portion of the book during the binding operation and to function as guides during the feed of the helical binder into the apertures of the book.

10. A machine such as defined in claim 6, in which said clamp is provided with an elongated cushioning member pivotally connected to said clamp and adapted to overlie the binding edge portion of the book to be bound, said cushioning member having a series of slots provided on its under surface, each of said slots being offset to substantially the same degree as the pitch of the coils in the binder to be inserted and having a bell-shaped mouth to assist the feed of the helical binder through the apertures of the book.

11. A machine such as is defined in claim 6, in which said clamp pivotally supports an elongated cushioning member having its under surface slotted to receive the upper portions of the coils of the binder being fed through the apertures of the book, the depths of said slots being less than the height of the portions of the coils projecting above the top surface of the book to enable said member to rest on the binder while it is being fed through the book.

12. A machine for binding books with helically-shaped binders and having, in combination, a table adapted to receive a book provided with sets of successive apertures arranged in a row along the binding edge of the book, means operable to arrange the pages of the book so that the sets of successive apertures define passageways which substantially conform in curvature to the curved portions of the helical binder which will extend therethrough, means for clamping the book as thus formed to the table, means for withdrawing said aperture forming means from the thus formed and clamped book, and means for forming and feeding a helically-shaped binder through the thus shaped sets of apertures after the withdrawal of said aperture forming means, said last-mentioned means comprising a die spaced from the book for forming a wire into a helical shape and guide means for the helically-formed wire having a length substantially equal to the distance between said die and the end of the book into which the binder will be initially fed and adapted to deliver the formed wire to the book accurately and without substantial vibration.

13. A machine such as is defined in claim 12, in which said die is provided with a bore having an internal helical groove to form the wire fed into the die and said guide is provided with a helical groove formed to receive the wire discharged by said die and to guide the formed wire to the place where it will be threaded into the first aperture of the book.

14. A machine as is defined in claim 12, in which said guide is a cylindrical member having an external groove formed to receive the wire formed by said die and to feed it into proper registry with the first aperture of the book, means for supporting said member on said die and means for adjusting said member relative to said die.

15. A machine for binding books with helically-shaped binders and having, in combination, a table adapted to receive a book provided with sets of successive apertures arranged in a row

along the binding edge of the book, means including a plurality of spaced hooked-shaped members operable to arrange the pages of the book so that the sets of successive apertures define passageways which substantially conform in curvature to the curved portions of the helical binder which will extend therethrough, means for clamping the book as thus formed to the table, means for withdrawing said hooked-shaped members from the thus clamped book, means for forming and feeding a helically-shaped binder through the thus shaped sets of apertures, means operative after the forming of the apertures in the book to render said feeding and forming means operative, and means for rendering said feeding and forming means inoperative after a predetermined period of operation, said last-mentioned means being controlled by said operative means.

16. A machine such as defined in claim 15, in which said feeding and forming means includes a pair of feed rollers normally inoperative to feed the binder member and controlled by said operative means, and in which said means for rendering said feeding and forming means inoperative includes a timing device, said last-mentioned means being controlled by said operative means to start the operation of said timing device and means controlled by said timing device to render said operative means inoperative to maintain the feeding relation of said feed rollers.

17. A machine for binding books with helically-shaped binders and having, in combination, a table adapted to receive a book provided with sets of successive apertures arranged in a row along the binding edge of the book, means operable to arrange the pages of the book so that the sets of successive apertures define passageways which substantially conform in curvature to the curved portions of the helical binder which will extend therethrough, means for clamping the book as thus formed to the table, means for forming and feeding a helically-shaped binder through the thus shaped sets of apertures, means operative after the forming of the apertures in the book to render said feeding and forming means operative, metering means, means controlled by said operative means for starting said metering means at the same time the feeding and forming means is rendered operative, and means controlled by said metering means for rendering said feeding and forming means inoperative after a predetermined period of operation.

18. A machine such as is defined in claim 17, in which the means controlled by said metering means is connected to and controls said operative means.

19. A machine such as is defined in claim 17, in which the means controlled by said metering means is connected to and controls said operative means and resilient means arranged to render said feeding and forming means inoperative immediately after said controlled means is actuated by said metering means.

20. A machine for binding books with helically-shaped binders and having, in combination, a table adapted to receive a book provided with sets of successive apertures arranged in a row along the binding edge of the book, means including a plurality of spaced hooked-shaped members operable to arrange the pages of the book so that the sets of successive apertures define passageways which substantially conform in

curvature to the curved portions of the helical binder which will extend therethrough, means for clamping the book as thus formed to the table, means for withdrawing the hooked-shaped members from the thus formed and clamped book, means for forming and feeding a helically-shaped binder through the thus shaped apertures, and means for cutting the binder from the wire being formed and for bending in opposed relation both ends of the binder to lock the binder in position on the book.

21. A machine such as defined in claim 20, in which said cutting and bending means includes a pivoted knife, a stationary blade associated with said knife and adapted to coact with the latter to cut the wire of the binder, and an anvil member adapted to coact with said knife after the wire has been cut to bend an end of the binder inwardly of the coils thereof.

22. A machine such as defined in claim 20, in which the cutting and bending means includes two spaced units, each of which is provided with a stationary blade, an anvil member and a pivoted knife adapted to coact with said blade to cut the binder wire and with said anvil member to bend the cut end of the binder, means for positioning said units in operative position and means for actuating said pivoted knives after the binder member has been threaded through the book.

23. A machine such as defined in claim 20, in which the cutting and bending means includes two spaced units, each of which is provided with a stationary blade, an anvil member and a pivoted knife adapted to coact with said blade to cut the binder wire and with said anvil member to bend the cut end of the binder, means for advancing said units into operative position, means for actuating said pivoted knives after the binder member has been threaded through the book, and means for retracting said units to an inoperative position.

24. A machine for binding books with helically-shaped binders and having, in combination, a table adapted to receive a book provided with sets of successive apertures arranged in a row along the binding edge of the book, a plurality of spaced hooked-shaped members adapted to enter into such sets of apertures and operable to arrange the pages of the book so that the sets of successive apertures define passageways which substantially conform in curvature to the curved portions of the helical binder which will extend therethrough, means for adjusting said table with respect to said book arranging means, means for clamping the book as thus formed to the table, means for withdrawing said hooked-shaped members from the thus formed and clamped book, means for forming a helically-shaped binder from a place spaced from the book and for feeding the same through the thus shaped apertures, means for guiding the wire through the apertures and for dampening vibration of the wire during its passage through the apertures, and means for cutting the binder to proper length and for bending the ends thereof inwardly into the end coils thereof.

25. A machine such as defined in claim 20, including means to render said feeding and forming means inoperative, said means being controlled by said book arranging means.

26. A machine for binding books with helically-shaped binders and having, in combination, a table adapted to receive a book having sets of successive apertures arranged in a row along

the binding edge of the book, guide means associated with said table for positioning the book so that the apertures thereof overlie a predetermined portion of the table, aperture forming means including pivoted positioning members adapted to engage sets of successive apertures in the book and to shape the same so that they define passageways which substantially conform in curvature to the curved portions of the helical binder which will extend therethrough, means for clamping the book as thus formed on said table, said clamping means being controlled by said aperture forming means, and means for feeding a helically-shaped binder through the thus shaped sets of apertures.

27. A machine for binding books with helically-shaped binders and having, in combination, a table adapted to receive a book having sets of successive apertures arranged in a row along the binding edge of the book, guide means associated with said table for positioning the book so that the apertures thereof overlie a predetermined portion of the table, aperture forming means including pivoted positioning members adapted to engage sets of successive apertures in the book and to shape the same so that they define passageways which substantially conform in curvature to the curved portions of the helical binder which will extend therethrough, means for clamping the book as thus formed on said table, said clamping means including a clamp body, a pair of guides slidably receiving the ends of said clamp body, spring controlled means provided on said clamp body and normally engaging said guides to support the clamp in raised position and means controlled by said aperture forming means and adapted to engage said spring controlled means to release the clamp after said pivoted positioning members have shaped the sets of apertures in the book, and means for feeding a helically-shaped binder through the thus shaped sets of apertures.

28. A machine for binding books with helically-shaped binders and having, in combination, a table adapted to receive a book having sets of successive apertures arranged in a row along the binding edge of the book, guide means associated with said table for positioning the book so that the apertures thereof overlie a predetermined portion of the table, said guide means including a pair of spaced guide members adapted to be engaged by the binding end of the book, means slidably supporting said guide members, means for advancing said guide members into position to be engaged by the book and means yieldably retaining said guide members in advanced position, aperture forming means including pivoted positioning members adapted to engage sets of successive apertures in the book and to shape the same so that they define passageways which substantially conform in curvature to the curved portions of the helical binder which will extend therethrough, means associated with said aperture forming means adapted to retract said guide members just prior to the engagement of the pivoted positioning members with the apertures of the book, means for clamping the book as thus formed on said table, and means for feeding a helically-shaped binder through the thus shaped sets of apertures.

29. A machine for binding books with helically-shaped binders and having, in combination, a table adapted to receive a book having sets of successive apertures arranged in a row along the binding edge of the book, guide means asso-

ciated with said table for positioning the book so that the apertures thereof overlie a predetermined portion of the table, said guide means including a vertically disposed plate adapted to engage with a side of the book, aperture forming means including pivoted positioning members adapted to engage sets of successive apertures in the book and to shape the same so that they define passageways which substantially conform in curvature to the curved portions of the helical binder which will extend therethrough, means operable to withdraw said plate prior to the entry of said positioning members into the apertures of the book, means for clamping the book as thus formed on said table, means for feeding a helically-shaped binder through the thus shaped sets of apertures, and means for automatically advancing said plate after the spiral binder has been threaded through the book.

30. A machine for binding books with helically-shaped binders and having, in combination, a table adapted to receive a book having sets of successive apertures arranged in a row along the binding edge of the book, guide means associated with said table for positioning the book so that the apertures thereof overlie a predetermined portion of the table, said guide means including a vertically disposed guide plate, aperture forming means including pivoted position- 25
